SANITARY PROTECTOR FOR ICE CREAM CONES

Filed March 7, 1940

UNITED STATES PATENT OFFICE

2,228,942

SANITARY PROTECTOR FOR ICE CREAM CONES

James Balton, Baltimore, Md., assignor to Maryland Baking Company Inc., Baltimore, Md., a corporation of Maryland

Application March 7, 1940, Serial No. 322,853

8 Claims. (Cl. 99—180)

My invention relates to the art of ice cream cone protectors, and it particularly has for its objects: to provide a paper cover for that portion of the stem of the cone which one grasps while eating the ice cream, to provide a protecting cover that can be easily and cheaply made, to provide a protector that can also be used to carry an advertisement, an identifying number, figure or other insignia; to provide a protector that will not come off when stacked cones are separated and yet to have the protector sufficiently loose on the stem of the cone to enable it to be easily torn off as the cone is being consumed or at any other desired time.

Other objects will in part be obvious and in part will be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawing, in which:

Fig. 1 is a perspective view of a cone with the invention applied.

Fig. 2 is an elevation of a cone with a jacket shown in section.

Fig. 3 is a view of the protector blank before being shaped and pasted or glued together.

Fig. 4 is an enlarged detail view, the cone and jacket being shown in elevation.

Fig. 5 is a view similar to Fig. 3 of a modified blank.

Fig. 6 is an enlarged detail view of a modification, the cone being shown in elevation and the jacket partly in elevation and partly in section.

Fig. 7 is a detail view illustrating one way to shape or form the lower end of the blank and to effect the gumming and knurling of the blank.

In the drawing, in which like numbers of reference indicate like parts in all the figures, 1 is the bowl of the cone, 2 the stem, 3 the tip, 4 the tip ring and 5 the nesting ring, all of which may be of the usual construction except that the ring 4 may be either continuous, or interrupted forming lugs 4a, and shaped to provide an abutment against which the lower edge 8 of the protector

will rest.

The protector comprises, preferably, a thin paper wrapper formed from a blank (Fig. 3) by wrapping it about a conical mandrel 13 (Fig. 7) and securing the longitudinal edges 9 by overlapping and gluing them together along narrow

areas 10 and knurling the joint, for example, by running a knurling wheel 16 on a shaft 17 along the joint (Fig. 7). The knurling 11 is of course done after the glue or paste has been applied; or, if desired, the glue or paste may be omitted, especially when very thin paper, such as that employed in making envelopes for wrapped drinking straws is used.

In order that the protector may be made to fit the stem 2 fairly close and yet permit it to pass wholly over the stop ring 4, or lugs 4a, its lower end 8 is provided with an area 12 which is rendered sufficiently yieldable to enable the jacket end 8 to be drawn up over the ring 4 or lugs 4a.

This may be accomplished in several ways, a preferred construction of the jacket being shown in Figs. 1 to 4 inclusive. In this form the diameter of the end 8 is less than that of ring 4. The pasted area 10 terminates short of the end 8 (see Figs. 1, 3, and 4) at a place where the diameter 20 of the jacket is about the same as that of the ring 4. Since the jacket edges 9 are not pasted together below the dot and dash line in Fig. 3 (the upper limit of resilient area 12) the lower end of the jacket will give (see dotted line Fig. 4) sufficiently to permit the jacket to be raised above the ring 4. As soon as the end 8 passes ring 4 it will close against the cone just above the ring, contracting to its normal diameter, and thus be held by ring 4 from being pulled off.

Aside from the fact that the protector 6 covers that part of the stem which is grasped by the hand and thus renders it more sanitary, it may contain a trade-mark, suitable advertising matter or may serve as a coupon in prize contests, etc.

This application is a continuation in part of my application filed December 4, 1939, Ser. 307,498.

From the foregoing description, taken in connection with the accompanying drawing, it is thought that the construction, application and advantages of the invention will be clear to those skilled in the art.

What I claim is:

1. In combination with a pastry cone having a stem, a nesting ring adjacent the open end of the cone and a second ring adjacent the tip of the cone, of a jacket for that part of the stem which is located between said rings and comprising a frusto-conical body the normal diameter of the smaller end of which is normally less than that of said second ring, the portion of the jacket immediately adjacent the lower end being sufficiently flexible to be drawn up over said second ring and then contract to substantially its

normal diameter whereby said second ring will serve as a stop to prevent accidental withdrawal of the jacket.

2. In combination with a cone having a stem,

• a nesting ring, and an abutment adjacent the tip spaced from the ring, a protector comprising a jacket for the stem composed of flexible material conforming to the shape of that part of the stem between the nesting ring and the abut-

10 ment, the lower end of the jacket having its lower end composed of a resilient frusto-conical portion the end of lesser diameter of which contacts the stem immediately above said abut-

15 ment whereby said lower end is capable of passing over the abutment in applying the jacket to the cone but will prevent accidental withdrawal of the jacket from the stem.

3. A cone protector, comprising a frusto-conical hollow flexible body the end of lesser diam-

20 eter of which is knurled and bent inwardly to constitute a yieldable restricted cone gripping area.

4. A protecting jacket for ice cream cones comprising a frusto-conical hollow flexible non-
25 stretchable body which is substantially nonex-
pansive laterally save for a portion adjacent the end of lesser diameter, which portion is slit longitudinally, by virtue of which said slit portion is somewhat expansible and contractible
30 for purposes described.

5. A protecting jacket for ice cream cones comprising a frusto-conical hollow flexible non-
35 stretchable body of a size snugly to fit the stem of an ice cream cone, said body being composed of a paper sheet having overlapping longitudinal edges secured together over a major portion of the length of the jacket from the larger end

toward the smaller end, by virtue of which the unsecured smaller end portion only is laterally expansible and contractible.

6. The combination with a pastry cone having a stem and a ring adjacent the tip end of the stem, of a jacket for snugly fitting the stem above the protuberance, said jacket comprising a frusto-conical body which is substantially non-expansive laterally save for a portion adjacent the end of lesser diameter, which portion is con-
10 structed so as to be sufficiently yieldable and resilient to pass up over said ring and then contract to a diameter less than that of the ring whereby the ring will prevent accidental withdrawal of the jacket.

7. The combination with a pastry cone having a stem provided with a protuberance adjacent the tip end of the stem, of a jacket for snugly fitting the stem above the protuberance, said jacket comprising a frusto-conical body which is substantially nonexpansive laterally save for a portion adjacent the end of lesser diameter, which portion is constructed so as to be suffi-
15 ciently flexible and resilient to pass up over the protuberance and then contract to a diameter less than that of the protuberance whereby the protuberance will prevent accidental withdrawal of the jacket.

8. A protecting jacket for an ice cream cone, comprising a frusto-conical hollow flexible non-
30 stretchable body of a size snugly to fit the stem of a cone, a relatively short portion of said body adjacent its end of lesser diameter being knurled and bent inwardly to constitute a yield-
35 able restricted cone gripping area.

JAMES BALTON.
